UNITED STATES PATENT OFFICE.

THOMAS LEE, OF CINCINNATI, OHIO.

VENTILATOR-HEAD.

1,231,627.

Specification of Letters Patent.

Patented July 3, 1917.

Application filed October 5, 1916. Serial No. 123,964.

To all whom it may concern:

Be it known that I, THOMAS LEE, residing at Cincinnati, Hamilton county, State of Ohio, have invented certain new and useful Improvements in Ventilator-Heads, of which the following is a clear, full, and exact description, attention being called to the drawing which accompanies this application and forms a part thereof.

10 This invention concerns ventilators of the kind used for carrying off bad air, smoke, etc., from the interior of inclosed spaces, buildings, etc.

They usually terminate above the roofs of 15 these structures where a head is provided which has an outlet opening by which communication with the open air is effected in a manner preventing at the same time entrance of rain and snow.

20 The invention relates more particularly to a type of ventilators in which this head has a lateral outlet which is contained in a hood or cowl rotatably mounted and which is provided with a vane adapted to be acted 25 upon by the wind whereby the hood is automatically adjusted to position the outlet with reference to the direction of the wind and where the outlet is provided with adjustable devices like dampers, shutters or 30 flaps also known as louvers to control passage through it and if desirable to close it altogether.

My invention involves the means for manipulating these adjustable controlling devices and it consists of these means and of 35 their construction as hereinafter described and claimed and as illustrated in the accompanying drawing in which:

Figure 1. is a central vertical section 40 through the ventilator-head taken so as to pass through the outlet opening thereof.

Fig. 2. is a rear-view of the same with parts broken away.

Fig. 3. is a horizontal section taken on line 45 3—3 of Fig. 1.

In the drawing letter A indicates the 50 cylindrical neck which is the lower or stationary part of the ventilator-head and whereby the same is secured in position either directly upon a roof or upon the

upper end of a ventilator shaft, stack or flue.

B indicates the hood or cowl which is the upper or adjustable part of the head. It has a depending collar 7 whereby it is 55 closely fitted around the outside of the upper part of the neck on which the head is so mounted that it may freely rotate thereon.

A post 8 forms the center of rotation and 60 is affixed within the head coincident with the axis of collar 7 and also coincident with the axis of neck A into which it extends.

Post 8 is held to its central position in the hood by any suitable means as for instance by two bearings formed in bars 9 and 11 vertically spaced and connected within the interior of the hood at right angles to each other. The post is held to these bars by any means as for instance by 65 nuts 12—12 at its upper end.

It is centered in the neck preferably in a similar manner and by two bearings also contained in two vertically spaced bars 13 and 14 connected at their ends within the 75 interior of the neck.

The weight of the hood is carried by a stirrup formed by a bar 15 attached to bar 14 with a space between the two and upon which stirrup the lower end of center-post 80 8 rests. It is also held positively to the neck by any suitable means as for instance, by a pin 16. By preference a hard, wear-resisting substance, like glass 17 is interposed to protect the stirrup by taking up 85 the contact with the lower end of post 8.

Above its lower cylindrical part the hood assumes the form of an elbow and terminates in a vertical plane beyond its collar 7 where it is open laterally and thereby forms 90 the outlet opening 18 of the ventilator-head. The cylindrical form may be retained around the turn and to the outlet or it may merge into the form of a prism and terminate with a four-sided outlet as shown. 95

Above the center of the outlet opening there is a vane 19 susceptible to the action of the wind and whereby the position of the hood is controlled to maintain the outlet opening in the lee of the wind for reasons 100

well understood, the hood being free to follow this action by turning on its central post 8 as described.

To prevent rain and snow from entering 5 the ventilator-shaft and also for the purpose of regulating the action of the ventilator-head, means are provided for controlling passage through the outlet, to reduce it or to cut it off entirely.

10 These means consist of flaps 20, sometimes also called louvers, and supported across the outlet opening by preference horizontally and parallel to each other.

Their support is in the nature of a hinged 15 connection at their ends, the pivotal centers of the connections being all alined, so that said flaps may also be alined with each other, and being of a width so that one flap with its free edge may slightly lap the adjacent flap, the outlet opening may thus be 20 completely closed when the flaps are so alined and as shown in Fig. 1.

From this position they may be adjusted to any degree of opening until the limit is 25 reached when they assume a position as shown in dotted lines in same figure when the outlet is fully open.

For the purpose of so moving these flaps 30 they are all connected to a shifter-rod 21 by means of links 22, so that when said shifter-rod is moved all flaps are simultaneously affected.

For so moving the shifter-rod I use a 35 lever 23 fulcrumed in any suitable manner as for instance, by supporting it on bar 11.

At its upper end it is connected to the shifter-rod and its lower end extends into neck A.

The flaps by reason of their weight and 40 the weight of the connected parts, (22 and 21) have a normal tendency to occupy a closed position as shown in Fig. 1. They are opened by action upon the lower end of lever 23 by means of a sliding follower 24 45 mounted on post 8 and in turn acted upon by a lever 25, supported in any suitable manner as for instance by means of bar 13.

This latter lever is conveniently manipulated from below by a pull device, chain 50 or rod 26, extended downwardly within accessible reach and it will be observed that the manipulation is effective at any time and in any position which hood B may occupy in view of its automatic rotary adjustment 55 on neck A. This is by reason of the inter-position of follower 24 which permits lever 23 to move around with the hood while remaining always subject to the action of lever 25. Observe Fig. 3.

60 That part of levers 23 and 25 which engages follower 24 is bifurcated as shown and engages the follower on each side of the center-post on which the follower slides so as to insure an even movement.

65 After the flaps have been opened it is

necessary to hold them so which is done by suitable locking means. I prefer to apply these means to the pull device which for such purpose, in part at least, consists of a rod as shown.

These locking means consist of a locking lever 27 pivotally supported at one end and provided with an opening through which rod 26 passes. This opening is somewhat larger than the diameter of rod 26 so that a 75 spring 28 below it may tilt it as shown in Fig. 2, in which position it binds on rod 26 and thus holds the same in position against vertical movement.

Another pull device which may be a rope, 80 chain or rod 29 is provided on the free end of the locking lever to manipulate the same.

When the outlet 18 is to be closed, it is only necessary to pull on rod 29 which 85 causes lever 27 to release rod 26 permitting the flaps to drop. When the flaps are to be opened or adjusted it is necessary to hold locking lever 27 down to release rod 26 for manipulation until adjustment of the flaps 90 has been accomplished.

The proper position for lever 27 at that time is determined by a stop 31 against which it is held. See dotted lines in Fig. 2.

This manipulation of rod 26 is always by 95 a pull and it is always in proper position for such purpose because its preceding release always leaves it in its high position.

Having described my invention I claim as new:

1. A ventilator-head comprising a stationary part, a hood mounted thereon for rotation and provided with an outlet opening for the head, adjustable controlling devices for this opening, an adjusting lever mounted in the hood and connected to these controlling devices, a manipulating lever mounted in the stationary part below the hood, means to transmit the action of the manipulating lever to the adjusting lever 105 and a pull-device on the manipulating lever 110 to actuate the same.

2. A ventilator-head comprising a stationary part, a post supported thereon, a hood carried on said post which forms the 115 center of its rotation, an outlet in said hood, controlling means for this outlet, a lever pivoted in this hood for adjusting these controlling means, a manipulating lever pivoted in the stationary part and a transmission device slidably supported on the post intermediate the two levers and adapted to transmit the actuation of the manipulating lever to the adjusting lever.

3. In a ventilator-head having an outlet 125 opening, the combination of flaps for controlling this opening which are adjustably supported to normally move into one of their extreme positions, means whereby they are connected for simultaneous move- 130

ment, a lever operatively connected to these means and adapted to actuate them for the purpose of adjusting these flaps to other positions, a pull device which comprises a rod to manipulate this lever, a locking lever adapted to engage the rod of this pull-device, a spring tending to hold this locking

lever in a tilted position and imparting to it a normal tendency to grip the rod mentioned and means to temporarily disengage 10 the locking lever to release said rod.

In testimony whereof I hereunto affix my signature.

THOMAS LEE.
